RECEPTACLE

Charles P. Wellman, West Medford, Mass.

Application March 4, 1930. Serial No. 433,010

9 Claims. (Cl. 229—34)

This invention relates to receptacles such as boxes, trays, covers, caps or cartons, formed of any foldable material, usually paper or cardboard, to blanks capable of being formed into such receptacles, and to an art of making receptacles. When I refer to a receptacle in this application I intend to include open-sided trays which may be closed by separate covers as well as receptacles having attached members for closing one or more sides.

Some objects of my invention are to provide a receptacle of foldable material in which the free edge of an end is folded over to improve the strength and neatness of the receptacle, in which gluing or otherwise affixing the end, the folded-over portion of the end and the glue laps or other wall-connecting flaps is facilitated, and which may be made by a series of severally simple operations capable of being performed by machinery.

Other objects of my invention are to provide blanks which comprise parts proportioned and related in a manner which is economical of material and which facilitates their formation into boxes, and to provide methods of manipulating foldable material to assemble, trim and reinforce receptacles in a rapid and easy manner.

Fig. 1 is a perspective of a receptacle of my invention having an improved end and side wall construction;

Fig. 2 illustrates a blank adapted to be formed into the receptacle shown in Fig. 1, and also illustrates diagrammatically the manner in which blanks may be cut from a strip of material;

Fig. 3 shows the blank of Fig. 2 with portions of the side and end-closure members folded over to provide turned and reinforced free edges;

Fig. 4 is a section on the line 4—4 of Fig. 1, and illustrates a preferable way of interfitting 40 of end closure elements of the receptacle;

Fig. 5 is a section on the line 5—5 of Fig. 4; Fig. 6 shows an alternate form of blank according to my invention;

Fig. 7 is a perspective view of a receptacle 45 constituting another embodiment of my invention;

Fig. 8 illustrates a blank adapted to be formed into the receptacle of Fig. 7; and

Fig. 9 shows the blank of Fig. 8 with portions 50 of its wall members folded over to provide turned and reinforced free edges.

In each of the improved receptacles of my invention the two ends may, if desired, be similar by utilizing symmetrical blanks as in Figs. 6 and 8, or blanks having opposite ends in re-

versed symmetry, as in Fig. 2. Accordingly it is not necessary to describe both ends of each blank, except to point out this preferable similarity between opposite ends of the various blanks.

Referring to Fig. 2, a blank of suitable foldable material such as paper or cardboard is marked by scores or folding creases 11, 12, 13 and 14 and transverse scores or folding creases 15d, 15e, 15f and 16d, 16e, 16f, into three wall sections, an intermediate or bottom section A, and outer side sections B and C, flexibly conjoined along their side edges, preferably extending in parallel directions, and adapted to be folded into the angularly related positions of Fig. 1.

At one or both ends of the blank I provide parts adapted to constitute a multi-thickness end closure including a principal end wall section extending in prolongation of one of these wall sections of the blank and a foldable flap joined to one edge of this principal wall section. In the embodiment of Figs. 1 to 6, this principal end wall section comprises a rectangular section D extending in prolongation of the outer side wall section C. A foldable flap G extends in a direction parallel to wall sections A, B, and C, and is joined to the principal end wall section D by a double crease 20 which enables it to be folded over and affixed by gluing or otherwise to the principal end wall section D as shown in Fig. 3. This principal end wall section D is adapted to be folded on the line 16d with respect to its adjacent wall section C, into the end closing position of Figs. 1, 4 and 5.

In order to affix principal end wall section D in this position, I provide one or more wall-connecting sections comprising integral flexible extensions of wall sections and capable of being connected to principal end wall section D, preferably in the manner of glue laps. In the embodiment of Figs. 1 to 6 such a wall-connecting section in the form of a glue lap E is provided at the end of wall section A, and a second such section F is provided at the end of wall section B. I prefer that the glue laps or other wall connecting sections thus provided be proportioned relative to the foldable flap G, (and to each other if more than one is provided) in such a manner that the one or more wall connecting sections 100 and the foldable flap G may overlie adjacent portions of principal wall section D without overlapping, and preferably will lie in the same plane in the relative positions shown in Fig. 4.

I deem it preferable to proportion and shape 110

the foldable flap G and the one or more wall connecting sections relative to each other in such a manner as to form a substantially continuous secondary reinforcement extending approximately across a dimension of the principal wall section D. For example, in Figs. 1 and 4, it will be apparent that glue lap E cooperates with foldable flap G to form a reinforcement extending across the height of the end of the box. Likewise the two glue laps E and F in this embodiment cooperate to form a reinforcement extending substantially across the width of the box.

In the illustrated embodiment of Figs. 1 to 6 wherein the end wall of the finished receptacle comprises the principal end section D, the trimming flap G, and the wall connecting sections E and F, the preferable relative proportions of these end wall forming elements may be expressed in the following manner, it being understood that the arrow x in Figs. 2 and 6 indicates the direction referred to as length, and that directions transverse to this arrow will be referred to in terms of width, regardless of the relative magnitude of length and width of elements of the box. The length of the principal end wall section D is preferably equal to the width of the intermediate wall section A. The length of the wall-connecting section E is preferably equal to the difference between the width of principal end wall section D and the width of trimming flap G. Wall-connecting section E is preferably cut out at its side adjacent the wall connecting section F as indicated at 28, an amount equal to the length of this wall connecting section F. Trimming flap G and wall-connecting section F are preferably beveled as indicated at 30, 31, at the exterior corners of the blank, to permit them to interfit as shown in Fig. 4. Thus in the preferable embodiment of my invention when the blank is closed into the box of Figs. 1, 4 and 5, the secondary reinforcement formed by the foldable flap G and the two wall-connecting sections E and F, covers substantially the entire area of the principal end wall section D and lies in juxtaposition thereto, and face to face therewith to form an end closure of substantially uniform double thickness.

By affixing the foldable flap G and any wall-connecting sections such as glue laps E and F employed, directly to the principal end wall section D, and without overlapping of the foldable flap and a glue lap, or of one glue lap with another, I am able to form an end closure in which the superposed elements to which pressure is applied in gluing are of uniform aggregate thickness. Pressure applied to these superposed elements is equally effective over all portions thereof, with a resultant improvement in the strength of the glued joint when the parts are affixed by gluing. This arrangement further enables me to provide a box having an end trimmed and reinforced by the provision of a turned free edge, and further reinforced by its including as an element or elements in addition to the principal end wall section, one or more glue laps, with the end of the box comprising only two thicknesses of material with respect to capacity and strength of the box.

The longitudinal sides of the box may be provided with reinforced and trimmed free edges by providing flaps K and L on the blank attached respectively to side sections B and C and adapted to be folded over upon these sides, as shown in Figs. 1 and 3. The opposite end of the blank of

Fig. 2 may, as indicated above, be provided with end-closure elements similar to those previously described, and is shown as comprising end-closure elements Da, Ea, Fa and Ga corresponding to elements D, E, F and G, and disposed in reversed symmetry thereto.

The blank of Fig. 6 differs from the blank of Fig. 2 only in that the end closure elements on its left end, as shown, are disposed symmetrically with respect to the end closure elements on its right end, instead of in reversed symmetry as in Fig. 2. The end closure elements on the left end of the blank of Fig. 6, since similar to the elements Da, Ea, Fa and Ga of the blank of Fig. 2 are designated by the corresponding reference characters Db, Eb, Fb and Gb. The end closure elements at the right end of the blank of Fig. 6 and the other sections of the blank are designated by the reference characters applied to the identical parts of the blank of Fig. 2.

In manufacturing the boxes, the blanks may be cut from a continuous web of material, as diagrammatically indicated in Fig. 2. Since in the assembled box (see Fig. 4) glue lap E extends across only a portion of the height of end section D, and glue lap F extends across only a portion of the width of end section D, these three elements D, E and F of the blank may be disposed as in Figs. 2 or 6, with their extremities in echelon, so that the blank has an end of stepped configuration. By this arrangement successive blanks may be cut from a continuous strip in interfitting relation and with a minimum of waste material, the stepped end of one blank being cut from material having a stepped end boundary defined by the similar end configuration of another blank. By disposing the end closure elements of the blank in reversed symmetry, as in Fig. 2, successive blanks, when cut, lie in the same position, not reversed. This constitutes a distinct advantage, since the blanks are in position to be presented successively to folding instrumentalities without reversal of alternate blanks or change in alternate operations of the folding machine. This feature is especially advantageous in making boxes from stock having coating, covering or printing intended in each box to appear invariably on the inner or the outer side, with the attendant impossibility of folding up alternate boxes toward opposite sides of the stock.

A preferable way of forming the box of Fig. 1 is to move the blanks of either Fig. 2 or Fig. 6 continuously in the direction of the arrow x (which also indicates the preferable direction of the grain of the stock), apply glue to successive edge members G, L, K and Ga (or Gb), and then fold over these edge members of the material upon the adjacent outer wall sections, in the manner shown in Fig. 3. Since side and end reinforcing or trimming flaps (for instance parts G and L) are located in substantial prolongation, they may be folded simultaneously and/or by the same instrumentality. Since in these blanks these flaps are folded in a direction perpendicular to the direction of travel of the blank, they may be turned over by a simple plow or folding device without substantial stopping of the forward motion of the blank. I consider it advantageous to be able to form the end reinforcing or trimming before or independently of the setting up of the walls of the box, since the material may be much more readily folded (especially by machinery) when in a flat blank than after it has been set up into a box.

The blank may now be erected into a box and

the ends of the box closed and affixed, preferably by means of a simple box-making machine of the usual plunger type. After positioning the end-closure elements D, E, and F, as shown in Figs. 4 and 5 with glue therebetween, a heavy compression may be applied firmly to glue these elements together. Since the reinforcing or trimming flap G has previously been folded over upon end wall section D, as explained above, this flap 5 G also receives the compressive force applied to the other end-closure elements, and a substantially continuous double-thickness end closure is strengthened by gluing under pressure in one operation. No hand or machine work subsequent 10 to this assembling operation is required to provide the turned and reinforced edges.

In the embodiment of Figs. 7, 8 and 9 end closure elements are connected to the wall sections of the box in a somewhat different manner from those of the previously described embodiments of my invention. Corresponding parts of the box and blank are indicated by the same reference characters employed in the previously described embodiments with the addition of primes. In the 20 box of Figs. 7, 8 and 9 the principal end wall section D' is attached to an intermediate wall section A', which may comprise for example, a top or bottom of a box, and wall-connecting sections such as glue laps E' and F', are attached to adjacent side sections B' and C' of the box. The side trimming and reinforcing sections L' and K' and the end trimming and reinforcing sections G' and G'a' may be folded from the position of Fig. 8 into the position of Fig. 9 by any suitable plow 25 or folding devices and preferably after the application of glue thereto. Thereupon the blank may be erected and fastened together in the position of Fig. 7. As in the previously described embodiment of my invention, a trimming and reinforcing flap G' and wall connecting sections in the form of glue laps E' and F' are here shown as shaped and proportioned to form in their folded state a substantially continuous secondary thickness superposed on the principal end wall 30 section D of the box. In this box, the advantages of strength and facility of gluing are obtained, and the end trimming or reinforcing may be formed on the principal end wall sections before or independently of the setting up of the box, 35 with the resulting advantages of facility of manufacture and capability of use in assembly of ordinary plunger type box machines.

While I refer for convenience to the "ends" and "sides" of my improved receptacles, I do not intend to infer that the ends of the receptacles must be, as shown, shorter than the sides, as obviously receptacles of many proportions may be made according to my invention.

I claim:

1. Receptacle-forming blank comprising conjoined intermediate wall and opposite side wall sections, a full sized end section joined to the end of one of said side wall sections and having a length equal to at least substantially the width of said intermediate wall section and being adapted to extend from one side wall section to the opposite side wall section and close the end of the receptacle upon erection of these sections, a trimming flap joined to an edge of said end section and adapted to be folded over upon the end section to provide a turned and reinforced free edge, and a connecting section joined to an end of another of said wall sections and adapted to connect its conjoined wall section to said end section, said trimming flap and said connecting

section being proportioned and arranged with respect to each other for interfitting, in juxtaposition to said end section so that the trimming flap, connecting section and end section may form a wall having no more than two thicknesses 80 of the blank material.

2. Receptacle-forming blank comprising conjoined intermediate wall and opposite side wall sections, a full sized end section joined to the end of one of said side wall sections and having a length equal to at least substantially the width of said intermediate wall section and being adapted to extend from one side wall section to the opposite side wall section, and close the end of the receptacle upon erection of these sections, a trimming flap joined to an edge of said end section and adapted to be folded over upon the end section to provide a turned and reinforced free edge, and a connecting section joined to another of said wall sections and adapted to connect its conjoined wall section to said end section, said trimming flap and said connecting section being proportioned and arranged with respect to each other and to their conjoined wall sections to lie in a common plane at an angle 95 to the intermediate wall section so that the trimming flap and connecting section do not overlie one another in a finished receptacle.

3. Receptacle-forming blank comprising intermediate wall and opposite side wall sections 105 flexibly conjoined along side edges, a full sized end section joined to the end of one of said side wall sections and having a length equal to at least substantially the width of said intermediate wall section and being adapted to extend from 110 one side wall section to the opposite side wall section, and close the end of the receptacle upon erection of these sections, a trimming flap joined to an edge of said end section and adapted to be folded over upon the end section to provide a 115 turned and reinforced free edge, a connecting section joined to the end of said intermediate wall section and a connecting section joined to the end of another wall section, each of said connecting sections being adapted to connect its 120 conjoined wall section to said end section, said trimming flap and said connecting sections being proportioned with respect to each other to lie in a common plane at an angle to the intermediate wall section so that the trimming flap does 125 not overlie the connecting sections in a finished receptacle.

4. Receptacle-forming blank comprising intermediate wall and opposite side wall sections 130 flexibly conjoined along side edges, a full sized end section joined to the end of one of said side wall sections and having a length equal to at least substantially the width of said intermediate wall section and being adapted to extend from one 135 side wall section to the opposite side wall section, and close the end of the receptacle upon erection of these sections, a trimming flap joined to an edge of said end section and adapted to be folded over upon the end section to provide a turned and reinforced free edge, a connecting section joined to the end of said intermediate wall section and a connecting section joined to the end of another wall section, each of said connecting sections being adapted to connect its conjoined 140 wall section to said end section, said trimming flap and said connecting sections being proportioned with respect to each other for interfitting, in juxtaposition to said end section so that the trimming flap does not overlie the connecting sections in a finished receptacle, all portions of the 145

trimming flap and the connecting sections thereby being capable of receiving pressure equally when these parts are being pressure-glued to the end section.

5. Receptacle-forming blank comprising conjoined intermediate and two opposite side wall sections disposed side by side and adapted to define three respective faces of a receptacle, two full sized end wall sections each shaped to define 10 and close a face of the receptacle, said two end wall sections being integrally joined to opposite ends of said two opposite side wall sections respectively, two connecting sections of less length than said end wall sections integrally joined 15 to the other ends of said opposite side wall sections and two connecting sections also of less length than said end wall sections and integrally joined to the ends of said intermediate wall, each of said connecting sections being adapted 20 in the finished receptacle to overlie and be fastened to the adjacent full sized end wall section.

6. Receptacle comprising a continuous sheet of material including conjoined intermediate wall and opposite side wall sections, a full sized single end section integrally joined to the end of one 25 of said side wall sections and extending to the opposite side wall section, completely to close the end of the receptacle, a trimming flap integrally joined to said end section and folded over there- 30 upon to constitute an end reinforcement and provide a turned free edge, a connecting section joined to the end of another of said wall sections and connected to said end section, said trimming flap and said connecting section lying in a common 35 plane in juxtaposition to and face to face with said end section.

7. Receptacle comprising a continuous sheet of material including conjoined intermediate wall and opposite side wall sections, a full sized 40 single end section integrally joined to the end of one of said side wall sections and extending to the opposite side wall section, completely to close the end of the receptacle, a trimming flap integrally joined to said end section and folded 45 over thereupon to constitute an end reinforce-

ment and provide a turned free edge, connecting sections joined to ends of the other two of said wall sections respectively and connected to said end section, said trimming flap and said connecting sections lying in a common plane in juxtaposition to and face to face with said end section.

8. Receptacle comprising a continuous sheet of material including conjoined wall sections, a full sized exterior end wall constituting an extension of the end of one of said wall sections and completely closing one face of the receptacle, a trimming flap constituting an extension of said exterior end wall and folded over thereupon inside the receptacle to constitute an end reinforcement and provide a turned free edge, connecting sections constituting extensions respectively of the ends of two of the exterior walls of the receptacle, said trimming flap and said connecting sections all lying in a common plane everywhere in contact with the inner face of said end wall and being secured thereto by adhesive without overlapping of said trimming flap and connecting sections.

9. Receptacle-forming blank comprising conjoined intermediate and two opposite side wall sections disposed side by side and adapted to define three respective faces of a receptacle, two full-sized end wall sections each adapted to define and close a face of the receptacle, said two end wall sections being integrally joined to opposite ends of said two opposite side wall sections respectively, two lateral connecting sections of less length than said end wall sections and integrally joined to the other ends of said opposite side wall sections, and two intermediate connecting sections comprising extensions of said intermediate wall section, said intermediate connecting sections being of a size less than said end wall sections and having shapes which accommodate the similar section of a similar blank 115 in prolongation thereof without substantially spacing the full-sized end section of one blank from the lateral connecting section of the other blank.
